UNITED STATES PATENT OFFICE.

THOMAS M. BALES, OF DUBLIN, INDIANA.

FANNING-MILL.

SPECIFICATION forming part of Letters Patent No. 453,532, dated June 2, 1891.

Application filed January 3, 1891. Serial No. 376,671. (No model.)

To all whom it may concern:

Be it known that I, THOMAS M. BALES, a citizen of the United States, and a resident of Dublin, in the county of Wayne and State of Indiana, have invented certain new and useful Improvements in Fanning-Mills; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of the invention and is a perspective view. Fig. 2 is a side elevation. Fig. 3 is a vertical section, and Fig. 4 is a detail view.

The invention relates to certain new and useful improvements in grain-cleaners; and it consists in the novel construction and combination hereinafter set forth.

The object of the invention is to provide a device of the character named which will have a maximum working capacity in proportion to its size, and, further, to so arrange the blowing mechanism and discharge as to prevent to a large extent the filling of the surrounding atmosphere with dust and chaff when in operation.

In the accompanying drawings, illustrating the invention, the letter A designates the supporting and inclosing frame, and B the hopper secured thereto. C is a gear-wheel journaled in one side of the frame and provided

with an operating-crank C'. D represents a fan-wheel driven by a pinion a, meshing with wheel C and inclosed in the casing D'. This wheel consists of the oppositely-curved fans or wings d and d'.

E E' are vertical bars or levers, one on each side and provided near their upper ends with vertical slots e e', adapted to receive and engage, respectively, projecting eccentric lugs b b', one on the outer surface of the pinion a and the other on the opposite end of the fan-wheel shaft.

F F' represent, respectively, the upper and lower shoes or shakers suitably supported in the frame and inclined from opposite ends and so arranged that the lower end of the upper shoe is directly over and but a short distance from the upper end of the lower shoe.

These shoes are connected, respectively, to the lower end portions of the bars E E' by means of suitable clips or irons f and pivot-pins 55 therethrough and receive a vibratory reciprocating motion therefrom. The upper shoe F is provided with one or more interchangeable screens G and a solid bottom G', in order that the grain may be carried to and discharged into the upper end of the shoe F'. This latter shoe has double screens of different grades for the purpose of separating the wheat into "first" and "second" grades. These screens are removable to provide for 65 the use of different grades or meshes.

h h are small strips pivoted in the lower shoe and which may be turned so as to throw both kinds of the grain to the same or different sides of the spout, so that they may be 70 discharged together or separately, as may be desired. The third grade or "screenings" will pass through the lower screen and be discharged through the spout h'.

H represents the chaff box or chute, having 75 a discharge-opening at H' on the side of the machine opposite the operating-crank. This chute is so arranged as to receive the entire amount of the dust and chaff from the grain as it passes from the hopper to the upper shoe 80 under the action of the blow-fan, which, with its curved wings, will give an upward and downward blast to the chaff, throwing it into the chute and out on the side of the machine opposite the operator, and thus prevent his 85 becoming covered with the dust, &c. By this arrangement, also, but a small fan or blow is necessary, thus requiring less power to run it. The chaff or dust, by being blown out before reaching the middle or screens in the shoes, 90 prevents their clogging up, thus giving the machine a greater capacity, and much less dust and chaff is thrown out into the surrounding air than in machines where the blast is forced up through the screens. 95

K K' are rods or bars pivoted at one end to the uprights z of the frame and at their opposite ends to the bars E E', respectively, at a point preferably somewhat nearer the upper shoe than the lower, in order to give a longer 100 stroke or movement of the latter than of the former shoe. This longer stroke is necessary for the lower shoe in order to keep the grain from clogging thereon. A rod L supports each

side of the lower end of said shoe and has a pivotal connection therewith, giving a lifting motion thereto when the parts are in operation to still further prevent clogging. These 5 rods are set at such an angle as not to be parallel with the rods E E', as such arrangement would prevent movement of the shoes to any extent.

It will be seen that the grain and chaff run 10 through this machine may be separated into four grades by one operation—viz., chaff, first and second grades, and screenings.

Having thus described my invention, what 15 I claim as new, and desire to secure by Letters Patent, is—

1. The grain-cleaner having its upper and lower shoes inclined oppositely to each other, the blast-wheel arranged above said shoes, slotted rods engaging eccentric pins or lugs 20 on the blast-wheel and pivotally connected to the shoes, and pivoted supports for the lower shoe, substantially as specified.

2. The combination, with the oppositely-inclined shoes and the blast-wheel arranged 25 above said shoes, of vertical slotted rods en-

gaging pins or lugs on said blast-wheel shaft and pivotally connected to said shoes, and horizontal rods pivoted to the frame and to said vertical rods at a point near the upper of the two shoes, whereby the length of a 30 stroke of the two shoes is varied, and pivoted supports for the lower end of the lower shoe, substantially as specified.

3. The grain-cleaner having its blast-wheel located above the upper shoe and having the 35 oppositely-curved fans or blades to give an upward and downward blast to the chaff as the grain passes from the hopper to the upper shoe, in combination with the chaff-discharge chute, also located to receive the chaff 40 above said shoes, said chute arranged to discharge at the side of the machine opposite to the operating-crank, substantially as specified.

In testimony whereof I affix my signature in presence of two witnesses.

THOMAS M. BALES.
